UNITED STATES PATENT OFFICE.

LOUIS PROLL, CHARLES M. DEPEW, AND EUGENE W. HAWLEY, OF SAN FRANCISCO, CALIFORNIA.

REVERSIBLE WINDOW.

SPECIFICATION forming part of Letters Patent No. 593,855, dated November 16, 1897.

Application filed May 13, 1897. Serial No. 636,343. (No model.)

To all whom it may concern:

Be it known that we, LOUIS PROLL, CHARLES M. DEPEW, and EUGENE W. HAWLEY, citizens of the United States, residing in the city and county of San Francisco, State of California, have invented an Improvement in Reversible Windows; and we hereby declare the following to be a full, clear, and exact description of the same.

Our invention relates to an attachment for windows by which we are enabled to turn or reverse the sashes about pivots centrally disposed in opposite sides, so that the windows may be turned at right angles with the line in which they ordinarily slide.

It consists in certain details of construction, which will be more fully explained by reference to the accompanying drawings, in which—

Figure 1 is a general view of the window. Fig. 2 is a vertical section through one side of casing and sash on line $z z$ of Fig. 4. Fig. 3 is a top view of the lower sash, showing the locking device. Fig. 4 is a horizontal section on line $x x$, Fig. 2. Fig. 5 is a similar section on line $y y$, Fig. 2. Figs. 6 and 7 show the arrangement of suspending the weight by chains.

In the construction of our device the sashes A, which are slideable with relation to the casings B of the window, are made of such a width from side to side as to allow them to turn between the parting-strips b of the casings B.

C is a groove or channel by which the sashes A are guided, and D are slides of a width equal to the thickness of the sash, having a length corresponding with that of the sash and adapted to slide in the grooves or channels C. To these slides the sashes A are pivoted at about the center by pivot-pins E, and as the sashes are no wider than the distance between the parting-strips b (the slides D filling the depths of the channels C) it will be understood that the sashes may when free be turned about their pivot-pins E, so as to stand at any desired angle, or be reversed to expose the outer surfaces to the interior.

In order to lock the sashes A to the sliding pieces D, we have shown the slides formed with channels F, extending vertically, and cor-

responding channels are made in the sashes. Within these channels in the sashes are fitted strips G, preferably of metal and of a thickness which will allow them to be moved into the slots F in the slides D, so that when in this position the sashes and the slides D will be locked together and will then be slideable up and down in the channels in the casing in the manner of any ordinary window. When the strips G are moved into the sash, so as to be disengaged from the sliding pieces D, the sashes will then be free to turn about their pivot-pins E, as previously described. These strips G have inclined slots H made in them, and these slots fit over pins I, which are fixed in the sashes, so that when the strips G are moved upwardly they will slide at the same time inwardly, by reason of the inclination of the slots H, until they lie entirely within the sashes, thus allowing the latter to be turned when thus released. When the strips G are again moved outwardly and downwardly, the outer edges of the strips G enter slots F in the sliding pieces D and thus lock the sashes to them. In order to conveniently disengage the strips G from the slides D, we have shown short lever-arms J fulcrumed or pivoted to the sashes, as shown at K, so that the outer ends project within reach of the operator, while the inner ends engage grooves or channels L in the strips G. It will be seen by this construction that the strips G will normally slide downwardly and outwardly upon the pins I by reason of the diagonal position of the slots H, and the outer edges of the strips will engage the channels F in the sliding pieces D and thus hold the sash and slides together. When it is desired to turn the window, it is only necessary to press upon the two thumb-pieces J upon opposite sides of the sash, when the strips G will be raised and by reason of the inclined slots drawn into the sash at the same time, so as to leave the latter free to turn about its pivot-pins E.

J' are projections fixed just below the lever-arms J, which enable the operator to grasp both between the thumb and fingers and thus exercise the necessary pressure to operate the levers J and disengage the strips G.

G. When the sash is restored to its normal position, the strips G will naturally drop into the slots in the slides D.

The sliding pieces D, to which the sashes are pivoted, may be connected with the counterbalance-weights by means of a cord or chain O. When the cord is used, an eye or loop may be formed at the end opposite to that to which the weight is attached, and this loop is slipped over a cylindrical projection P, which has a flange P' upon the outside, this flange and the cylindrical portion being countersunk into the slide D and secured by screws or otherwise.

15 The pivot-pins E form extensions from the center of the part P, and their inner ends project into socket-pieces upon which the sashes turn, as previously described.

In some cases chains are used in place of the cords, in which case an extension P² is made from the upper part of the cylindrical portion P, having a transverse channel made in it, as shown at R. This channel is of such shape that the cylindrical end of the 25 link may be slipped into it, the shank passing upwardly through a narrower portion of the channel, which extends to the top of the extension P². A pin S is then placed behind the head of the chain-link, and this prevents its being withdrawn. A rope or chain extends upwardly in a groove or channel formed in the slide D and passing over the usual direction-pulleys connects with the weight at the opposite end. In order to lock 30 the upper and lower sashes when the windows are closed, we have shown a lever-arm T fulcrumed upon the top of the lower sash, as shown at U. This lever-arm carries a pin or equivalent locking device T' at the end, 40 which is adapted to engage a hole or locking device in the other sash. This lever is normally acted upon by a spring V, which, when the lever is free and the pin T' in line with the hole or engaging device in the other sash, 45 will cause it to engage and thus lock the sashes together. In order to disengage this lever when it is desired to move the sashes, an inclined projection W is formed upon the upper end of the sliding strip G, so that when 50 these strips are moved to draw them into the sash and disengage them from the sliding pieces D, this incline will act upon the end of the lever T which is adjacent to the sliding strip G, and will thus press that end of the 55 lever against the tension of the spring V, and, correspondingly moving the opposite end, will disengage the locking-point T' from the other sash, thus allowing the sashes to be moved independently of each other.

60 Having thus described our invention, what we claim as new, and desire to secure by Letters Patent, is—

1. In a window, vertically-slidable sashes, pieces fitting channels between the parting strips in the window-casing, pivot-pins by which the sashes are connected with the slides and turnable about the pins, grooves or chan-

nels made in the slides and the edges of the sashes in line with each other vertically, slideable strips fitting said grooves or channels 70 having diagonal slots movable upon fixed pins at the upper and lower ends whereby the upward and diagonal movement of said strips upon the pins depresses them into the sash-slots and disengages them from the slides and 75 the downward movement correspondingly projects them from the sashes and causes them to engage and connect both the sashes and slides, and levers fulcrumed to the sashes, each having one end to engage one of the 80 strips and the opposite end projecting through the inner edge of the sash, for raising said strips to disengage.

2. In a window, vertically-slidable sashes, independent pieces slideable in guides or channels in the window-casings and pivot-pins by which the sashes are turnably connected therewith, grooves or channels made in the slides and in the sashes, slideable strips fitting said grooves or channels having diagonal 90 slots at the top and bottom, and stationary pins extending into the slots whereby the upward movement of the strips disengages them from the sliding pieces to which the sashes are pivoted and the downward movement 95 causes them to be projected and engaged therewith, levers engaging said strips projecting through the inner edges of the sashes and corresponding projections fixed to the sashes with relation to the lever M so that the 100 two may be grasped simultaneously to form a purchase to operate the levers.

3. In a window, vertically-sliding sashes, corresponding slides fitting grooves or channels in the casing and slots made in the slides 105 and the edges of the sashes with strips movable to engage the two or disengage them, pivot-pins connecting the sashes with the slides whereby the sashes are turnable about said pins, and extensions of the pins outwardly whereby they are fixed to the slides, said extensions forming attachments for the counterweight cords or chains.

4. In a window, vertically-slidable sashes detachably engaged with slides which are adapted to travel in grooves or channels formed in the window-casing, pivot-pins fixed to the slides and extending into sockets in the sashes whereby the latter are turnable upon said pins when the locking devices between the sash and the slides are disengaged, extensions from the pivot-pins having sockets adapted to receive enlarged heads upon the chain or cord whereby the latter is connected with the pivot-pins and slides.

5. In a window, vertically-slidable sashes, slides fitting in grooves or channels in the casing, pivot-pins uniting the slides with the sashes whereby the sashes may be turned horizontally about said pivot-pins, strips fitting channels made in line with each other in the slides and the sashes, inclined slots made in the strips and slideable upon fixed pins with means whereby the strips may be raised and

sunk into the channels in the sashes so as to disengage them from the slides, or allowed to drop and be projected from the sashes and engaged with the slides, locking-levers ful-
5 crumed to the top of the lower sashes having projections adapted to engage with the lower rail of the upper sash, and inclined lugs upon the locking-strips adapted to engage the lever and turn it to unlock the sashes when the
10 strips are raised to disengage the sashes from the slides, and a spring whereby the lever is

actuated to again lock the sashes when the strips are allowed to drop and connect the sashes and slides.

In witness whereof we have hereunto set 15 our hands.
